UNITED STATES PATENT OFFICE

2,491,295

PEENING HAMMER HAVING REMOVABLE
STRIKING HEAD

Norman Anderson, Duluth, Minn.

Application November 5, 1945; Serial No. 626,856

2 Claims. (Cl. 145—29)

1

This invention relates to improvements in a peen for a hammer head and has special reference to such a device applicable to a hand hammer, used in the art of repairing automobile fenders or the like, in restoring the normal appearance of the surface of a previously dented, bent or otherwise damaged fender, or body of an automobile.

It is well known that when such force is applied either by hand or otherwise to deranged thin metal sheets, such as automobile fenders, it becomes very hard to bring the surface of the metal back to normalcy without leaving an impression thereupon of the face of the tool employed.

In other words, it is very hard in many instances to judge correctly the contour of the surface being engaged by the face of the hammer to avoid such defacement, and to overcome this problem is the principal object of the present invention.

Another object is to so shape the co-operative parts of the peen of such a hammer that they will most readily function to hold the jointed parts thereof in close ideal working position at all times as well as more readily assume normal axial relation of the face of the peen to the head of the hammer.

Other objects and advantages will appear during the further description of the embodiment here illustrated.

Referring now to the accompanying drawing forming part of this application:

Fig. 1 is a side elevational view of one type of hand hammer head with one of the improved peens shown in vertical section upon one terminus of said head, and

Fig. 2 is a transverse sectional view on the line 2—2 Fig. 1.

In the drawing, 1 represents the head of the hammer comprising the two opposed axially aligned shank-like portions 2 and 3.

The shank 3 adjacent its extreme end is preferably reduced in diameter somewhat as at 4 and the extreme end is enlarged and of semi-spherical shape as at 5 with its greatest diametrical dimension somewhat more than that of the reduced adjacent shank portion 4 to provide the flat stepped ledge or annulus 6 as a seat for the smaller end of the conical expansive spring 7.

Now the peen proper comprises the cylindrical hollow body portion 8 with the spring chamber 9 therein and the circular head portion 10 preferably somewhat larger in diameter than the body portion and terminating in the slightly convexed

2

face 11. The head 10 has formed therein a central semi-spherical seat for rockable reception of the semi-spherical terminus 5 of the hammer head. This seat is of somewhat less depth than the terminus 5 in order to insure a free stepped seat about the shank portion 4 for the spring 7 on the annulus 6.

The circular entrance 12 into the chamber 9 obviously must be slightly larger in diameter than the terminal member 5 so as to allow free passage therethrough of the latter, thus there is formed the circular ledge 15 above the entrance to the chamber and therein for suitable impingement for the larger extremity of the spring 7 in its constant action of keeping the peen in ideal working contact with the shank of the hammer head.

The spring 7 is of a size and strength to be readily slipped over the enlarged terminus 5 of the hammer head shank, then contracted sufficiently and tucked into the chamber 9 through the entrance 12 until it readily assumes its proper functioning position as shown.

As convenience in removal of the spring 7 when occasion arises for such, there is provided the cut or slot 13 which extends diametrically across the open end of the peen and through the spring ledge 15 most clearly seen in Fig. 2 of the drawing and through either extremity of which the largest upper coil of the spring is accessible as by a small pointed instrument such as a small file shank or the like for compressing the spring and working it upwardly out of the chamber 9 simultaneously with the terminal 5 of the hammer shank.

The inner end 14 of each terminal portion of the slot 13 is slightly flared to obviate the possibility of same being restricted by repeated engagement with the shank portion 4 during the hammering process material in actual practice.

From the foregoing it is apparent that the paramount feature is that of keeping the work-engaging portion of the peen in constant frictional, but yieldable rockable engagement with the shank portion of the hammer head during the hammering process and which provision has proved material in actual practice.

Another notable feature in this type of peen when in actual use is the fact that at every retraction of the hammer head from a blow which had made the peen function at all out of its normal axial alignment, it would immediately reassume such a normal alignment for a subsequent blow, which obviously is essential to the success of the tool.

Applicant has determined that the spring being

of conical shape has a much greater tendency to maintain the peen in its proper normal axial alignment with the hammer shank, than a plain coil spring.

What I claim is:

1. A new article of manufacture: a hammer head including a cylindrical shank portion, a portion of said shank adjacent one end thereof being of reduced diameter, the end surface of said end of the shank being semi-spherical and of a diameter greater than said portion of reduced diameter to provide an annular spring seat at the juncture of said semi-spherical portion with said portion of reduced diameter, a hollow one piece peen on said end portion and having a substantially semi-spherical recess formed in the inside surface of one end of said peen to rockably receive said semi-spherical end of the shank, the outside surface of said end of the peen forming a slightly curved peening surface, the opposite end of said peen having an opening forming an entrance portion to the chamber of said peen, said opening being substantially in axial alignment with said recess and of reduced size to the transverse dimension of said chamber but of a size to freely admit the end of said shank whereby a spring engaging seat is provided about said entrance, a conical expansive spring within said chamber and about said shank and with its smaller terminus impinging said spring seat on said shank and the opposite terminus impinging said spring seat on the peen to bias said peen and hammer head towards each other, and a diametrically disposed slot through the open end of said peen for convenience in removing said spring.

2. A hammer head including a cylindrical shank portion formed integral therewith, a portion of said shank adjacent one end thereof being of

reduced diameter, the end surface of said end of the shank being semi-spherical and of greater diameter than said portion of reduced diameter providing an annular spring seat at the juncture of said semi-spherical portion with said portion of reduced diameter, a one-piece hollow peen on said end portion and having a semi-spherically shaped recess formed in the inside surface of one end of said peen to rockably receive said semi-spherical end of the shank, the opposite end of said peen having an opening forming an entrance to the chamber of said peen, said opening being substantially in alignment with said recess and of reduced size to the transverse dimension of said chamber but of a size to freely admit the end of said shank so that a spring seat is formed about said entrance, a conical expansive spring about said shank within said peen and having its smaller end engaging said spring seat on said shank and its larger end engaging said spring seat about said entrance on said peen to bias said peen and shank in engagement and normally in axial alignment, and a transverse diametrical slot through said opposite end of said peen for more convenient access to said spring to remove same from within said hollow peen when required.

NORMAN ANDERSON.
